WASSILI GORDIN, OF ST. PETERSBURG, RUSSIA, ASSIGNOR TO THE FIRM C. NENADER,
OF ST. PETERSBURG, RUSSIA.

LIQUID-FUEL BURNER.

1,085,334.

Specification of Letters Patent.

Patented Jan. 27, 1914.

Application filed January 13, 1912. Serial No. 671,122.

To all whom it may concern:

Be it known that I, WASSILI GORDIN, a subject of the Czar of Russia, and residing at Wassili Ostrow, 18 Linie, St. Petersburg, Russia, have invented certain new and useful Improvements in Liquid-Fuel Burners, of which the following is a specification.

This invention relates to apparatus for burning liquid fuel in furnaces, of the type in which the fuel is received upon a rotating surface of a centrifugal sprayer, which is arranged in a casing to which air is supplied, the surface throwing the fuel off in the form of a spray by centrifugal action.

15 The present invention consists in an improved apparatus of this kind, in which the centrifugal sprayer is provided with a circumferential surface, as distinguished from a transverse surface, and the liquid fuel is introduced into the casing in such a manner as to impinge directly upon this circumferential surface. The liquid fuel is preferably introduced into the casing in a direction perpendicular to the axis of the sprayer.

25 In the accompanying drawings is illustrated by way of example one embodiment of the present invention.

Figure 1 is an end elevation of the arrangement in partial section at A—B of Fig. 2. Fig. 2 is a plan. Fig. 3 is a sectional elevation at C—D of Fig. 4 looking toward the outlet. Fig. 3^a is a sectional elevation at G—H looking toward the outlet. Fig. 4 is a section at E—F of Fig. 3.

35 1 is a casing tapering forwardly which can be located within the firing space of a furnace. The casing 1 is closed at the rear end by means of a dome 2 the end of which is closed by a grating 3. The dome supports 40 a shaft 7 in suitable bearings 5 and 6, on which shaft are mounted rotating surfaces 11—12 to which the liquid fuel is supplied through a tube 13 provided with a cock 32. On rotation of the shaft 7 the liquid is 45 thrown off tangentially from the surfaces 11—12 and partly burnt while the unconsumed sprayed liquid particles arrive at the heated surfaces of the casing 1 and are vaporized. The smaller the distance between the vaporizing surface and the spraying device the smaller is the portion of the combustible which is burnt on its way to the vaporizing surface and vice versa. The shaft 7 may be driven by means of a turbine 9 located in the dome at the rear end

of the casing 1 which turbine is supplied with steam from a nozzle 14 at the end of a pipe 15 leading to a steam generating space 16. This latter is closed by means of a cover 17. The supply of water for the steam generator is effected through a pipe 20 with a cock 21.

The turbine wheel 8 is open at the center and in this opening 10 is formed a fan 10^a for effecting the delivery of fresh air. The current of air is increased by a fan 11^a which is arranged at the middle of the spraying device 11—12.

70 The adoption of fans renders the combustion entirely independent of the height of the chimney and thus allows the arrangement to be used in all cases where an artificial draft is indispensable or desirable.

Having now described my invention what I claim as new and desire to secure by Letters Patent is:

75 1. A liquid fuel burner, comprising a casing, a rotating centrifugal sprayer in said casing, a turbine for driving said sprayer, located at a point distant therefrom, a central aperture in the rotor of said turbine, and a fan arranged therein for producing a draft through said casing.

80 2. A liquid fuel burner, comprising a combustion chamber, a rotating centrifugal sprayer in said combustion chamber, means for introducing liquid fuel to said sprayer, a turbine for driving said sprayer, a steam generating pocket located on the exterior of the wall of the combustion chamber adjacent the point at which the fuel is burned, and means for conducting the steam generated in said pocket to said turbine, for driving the same.

85 3. A liquid fuel burner, comprising a casing, a rotating centrifugal sprayer in said casing, consisting of a plurality of plates which are of dished shape to form circumferential surfaces, and means for introducing liquid fuel into said casing and causing it to impinge on said circumferential surfaces.

90 4. A liquid fuel burner, comprising a combustion chamber, an annular centrifugal sprayer in said chamber, means for supplying liquid fuel to said sprayer, an annular steam turbine for rotating said sprayer, means associated with the combustion chamber for generating steam to drive said turbine, and a pair of fans, one of which is

arranged in the central aperture of the turbine, and the other of which is arranged in the central aperture of the centrifugal sprayer.

5. A liquid fuel burner, comprising a casing, a dome at the rear end thereof, a shaft arranged axially of the casing and supported in bearings carried by said dome, an annular centrifugal sprayer mounted on said shaft within the casing, a pipe for supplying liquid fuel to said sprayer, a steam turbine having an annular rotor on the other end of said shaft within said dome, a steam

generating pocket in the walls of said casing, a pipe for conducting steam from the pocket to the turbine, a fan in the central opening of the turbine rotor for creating a draft through said casing, and a second fan arranged in the central opening of the centrifugal sprayer, for increasing the draft.

In testimony whereof I affix my signature in presence of two witnesses.

WASSILI GORDIN.
